United States Patent Office.

WANNIBALD R. BOERNER, OF CHICAGO, ILLINOIS, ASSIGNOR TO HIMSELF
AND CARL R. BOERNER.

Letters Patent No. 71,573, dated December 3, 1867.

IMPROVED WIRE FIGURE.

The Schedule referred to in these Letters Patent and making part of the same.

TO ALL WHOM IT MAY CONCERN:

Be it known that I, WANNIBALD R. BOERNER, of Chicago, in the county of Cook, and State of Illinois, have invented a new and useful Improvement in Wire Figures for displaying dry-goods for ladies' wearing-apparel; and I do hereby declare that the following is a full, clear, and exact description of the same, reference being had to the accompanying drawings and the letters and figures marked thereon, which form a part of this specification, and in which—

Figure 1 represents a front elevation of my invention.

Figure 2, a side elevation of the upper portion of said figure; and

Figure 3 is a top view of the lower portion of said figure.

The nature of my invention consists in a novel construction of a wire figure, in which the wires which form the skirt serve also as the stand or support of said figure, thus doing away with the ordinary central supporting-stand of such figures, and making a figure much less liable to be upset.

To enable those skilled in the art to manufacture and use my invention, I will proceed to describe the same with particularity.

The same letters of reference refer to the corresponding parts in the different figures.

The upper part or waist of my wire figure is made in the ordinary way and form, excepting it is made of sufficiently strong wire to support the goods without a central post or support. There is a heavy and strong metallic hoop, B, to which the wire A is fastened by means of the bolts and nuts C. The wires D of the waist are fastened to the wire A, and rest upon the hoop B, when the figure is put together. There is also a strong metallic hoop, E, which forms the bottom of the figure, said hoops B and E being connected together by the wires F, which form the ordinary hoop-skirt of wire figures, and at the same time are sufficiently strong to support the figure and the goods displayed thereon. The whole figure is supported upon ordinary casters H.

By this construction the central supporting-post and stand are dispensed with, thus making the figure simple and cheap, and at the same time the figure stands upon so broad a base, supported upon casters, that it is not liable to be upset while being moved about to display the goods, which is a very decided objection to all the ordinary wire figures.

Having thus fully described the construction and operation of my invention, what I claim, and desire to secure by Letters Patent, is—

1. I claim a wire figure, composed of the removable waist and lower part without a central support or pedestal, substantially as and for the purposes set forth.

2. I claim the removable waist D, provided with the wire A, in combination with the lower part F, provided with the strong metallic hoops B and E, as and for the purposes specified.

WANNIBALD R. BOERNER.
